UNITED STATES PATENT OFFICE.

JAMES W. BRYCE, OF BLOOMFIELD, NEW JERSEY, ASSIGNOR TO THE TABULATING MACHINE COMPANY, OF ENDICOTT, NEW YORK, A CORPORATION OF NEW JERSEY.

RECORD-CARD-CONTROLLED MACHINE FOR SORTING AND THE LIKE

Application filed November 19, 1924. Serial No. 750,732.

This invention relates to machines especially adapted for sorting record cards in tabulating systems which use the Peirce combinational hole system of index point perforations, as distinguished from cards of the Hollerith type which use a single hole differentially positioned in the card column.

In the Peirce system the reading position is a particular zone on a card and the holes 10 are variously arranged in that zone instead of being positioned anywhere in a card column extending from top to bottom of the card, as in the Hollerith.

My present invention is an improvement 15 on the machine described in detail in patent to E. A. Ford, No. 1,657,654 dated January 31, 1928, and my patent No. 1,651,179 dated November 29, 1927 which disclose sorters of the horizontal type, designed to sort Hollerith and Peirce cards electrically and deposit each class in its proper station.

My present invention is a sorter for Peirce cards, in which it is possible with one run of cards through the machine to first take out all 25 cards having a certain combination of digits in a plurality of columns in a certain zone on the cards, and then, if desired, sort the remaining cards into the regular 0, 1, 2, 3, 4, 5, 6, 7, 8, 9, and reject stations, in the usual way.

Further and other advantages of the present invention will hereafter appear in the accompanying specifications and claims and in the drawings, which by way of illustration show what I now consider to be a preferred 35 embodiment of the invention.

Fig. 1 is the front elevation of a sorting machine to which my device is adapted.

Fig. 2 is a section through the feeding mechanism, showing also some conveyor rolls, 40 and the analyzing or sensing devices for the first two stations, which are the multiple digit stations.

Fig. 3 is an extension of Fig. 2 to the left showing additional rolls, and some of the 45 sorting devices for the single digit stations.

Fig. 4 is a plan view of a portion of Fig. 2, showing rolls and drives therefor, a set of multiple digit brushes and its plug board, and other details.

Fig. 5 is a plan view of a portion of Fig. 3 showing rolls and drives therefor, brush holder for single digit stations, and other details.

Fig. 6 is a cross section through a card and

a set of multiple digit contact pads, also details of the wiring to the plug board.

Fig. 7 is a plan view showing arrangement of multiple digit contact pads.

Fig. 8 is a detail of the worm gear drive of the rolls.

Fig. 9 is a typical Peirce record card showing combinational perforations in the control zone.

Fig. 10 illustrates the Peirce code.

Figs. 11 and 11^a together form a diagram of the electric circuits of my invention.

Referring to Fig. 1, the frame 30 is mounted on legs 31. Underneath the main frame, and carried by the legs, is a shelf or subframe 32 supporting the motor 33, which drives the 70 machine from pulley 34 by belt 35 to pulley 36 fast to shaft 37, which runs the full length of the machine, in the rear, pulley 36 being on one end of it and handwheel 38 on the other.

In operation a stack of cards to be sorted is 75 placed in the feed magazine, as at 55, the operator adjusts his analyzing brushes, and when the motor is started the picker drum feeds the card, one by one, from the bottom of the stack into the conveyor rolls, which carry 80 them along horizontally above the receiving stations until each card is deflected downwardly into one of the receiving stations, which are fully described in the patent to E. A. Ford, above referred to.

The feed mechanism consists of the rotary 85 picker drum 61, driven from shaft 37. Drum 61 carries in its rim a number of picker blades 69 extending lengthwise of the drum and projecting therefrom a distance slightly less than 90 the thickness of a card. As the drum revolves, each blade in turn picks a card from the bottom of the stack 55 and feeds it through the micrometer openings 72 provided between the bottom of fixed plate 73 and rollers 74, into the control of the conveyor rolls.

The upper conveyor rolls are designated 82, there being two of them fast on shaft 83, while directly under each of these rolls is a lower roll 84 fast on shaft 85. The rolls 100 are driven by worms 86 on shaft 37, through spiral gears 87 fast on shafts 83 and 85. All rolls are driven at the same speed and are of the same diameter, the upper sets turning clockwise and the lower sets counter-clockwise so as to draw the cards between them. Each upper pair of rolls is downwardly spring-pressed against the corresponding 105

lower set by adjustable spring clips 92. It is found that this conveyor system insures that the exact distance between cards will be maintained throughout their travel, which is an essential feature in the operation of my invention.

Record card.

The Peirce combinational hole system may

10 be understood by reference to Figs. 9 and 10, which show a typical control zone of a card, and the Peirce code for numbers, respectively.

15 An inspection of Fig. 10 shows that the use of either one or two holes, and four positions, can be made to designate all of the digits 0, 1, 2, 3, 4, 5, 6, 7, 8, and 9. For convenience of description I have designated the four positions by letters A, B, C, and D. 20 Reference to Fig. 10 shows that a single hole in D position means 0, while a single hole in A position means 1; in B position the single hole means 2, and in the C position 5. Two holes, one at A and one at C, mean 3, while 25 two holes, one at C and one at D, mean 9, and so on.

This code enables us to interpret the meaning of the holes in the card itself. For instance in the column furthest to the left we 30 find holes in A and B positions, which means 7; in the second column holes at B and D mean 4, while in the third column holes at B and C mean 8, and so on.

35 *Single-digit analyzing and distributing system.*

In the embodiment of my invention herein described, the card, on being fed from the stack, passes first through two plural-digit 40 analyzing stations and then passes to the ten single-digit and reject stations.

For convenience and clarity of description I shall first explain the single-digit portion of the machine and later describe those features of the invention which pertain especially to the plural-digit system.

Crosswise of the frame of the machine and fastened thereto at their ends, are a plurality of rods 100, one for each single-digit station. These rods are parallel to shafts 83 and in approximately the same plane. Each 50 rod carries a brush holder 101 (Fig. 5) of non-conducting material, settable lengthwise on rod 100, and secured thereto by screw 102, or other suitable means. Each brush holder carries either one or two contact brushes 104, which bear on the top surface of cards 103 passing between the conveyor rolls. The rods 100 are so placed that each card passes under 55 a set of brushes 104 just before it reaches each receiving station, as will be more fully described. If no card be present, each brush 104 rests on a metallic contact strip 105, supported by the non-conducting block 106 rigidly 60 secured to the frame of the machine.

There is an individual contact strip 105 for each individual brush.

These contact blocks 106 and their corresponding brushes, are exactly a card cycle apart, so if the control zone of any card in 70 the conveyor system is under a set of brushes, then the control zone of every card passing through the rollers is also under a set of brushes.

Cards are fed bottom first, and the sets 75 of brushes are arranged according to the Peirce system so that the first set from the right will sense 9, the second set will sense 8, the third set 7, and so on in the order 6, 4, 3, 2, 1, 0, and 5. The 5 is placed out of 80 its regular numerical order so that the cards will pass under all the two-brush code combinations before passing under the single brushes, otherwise the single brushes might sort out some two-hole combinations, as will 85 appear from later description. The above arrangement will be apparent from Figs. 2 and 3, in which I have lettered the four brush positions A, B, C, and D, to correspond with Fig. 10. It will be noticed that the two 90 brushes in the station to the right in Fig. 3 are in B and D positions, which means 4; at the middle station they are at positions A and C, which means 3, while at the station to the left the single brush is in B position, 95 meaning 2. This will also be apparent from Figs. 11 and 11^a, in which the brushes are shown in full lines and the vacant brush positions are dotted. For instance, at station 0 there is a brush and contact strip at position D only, whereas at station 3 there are 100 brushes and contact strips at A and C.

Adjacent each receiving station except the final, or reject, station, is a magnet 107 with its coil in series with the brush or brushes of that station. Controlled by each magnet is 105 a deflector plate 108, hinged at 109 and carrying downwardly extending arm 110 drawn to the right by spring 111.

On the same shaft with picker drum 61 is a 110 four-lobed cam 112. Extending lengthwise of the machine is a push rod 113, actuated by cam 112 through roller 114 carried by block 115 on the end of rod 113. The rod 113 is pushed to the left by the cam, and returned 115 by spring 116, four times for every revolution of the picker drum, or once for every card cycle.

At each receiving station except R, the 120 push rod carries a pin 117 so positioned that when rod 113 is pushed to the left, pin 117 will carry with it arm 110, which is rigidly attached to deflector 108, and thereby lower the upper end of the deflector below the plane of passing cards.

Each magnet is provided with an armature 118 carried on one arm of a lever 119, pivoted at 120, and having at its end a shoulder 121. This arm of the lever is normally held in raised position by the spring 122 130

pulling downwardly on the opposite end of lever 119.

When pushed to the left by pins 117, arms 110 are latched on shoulders 121 of lever 119, and deflectors 108 are below the plane of passing cards. This is normal position. If, however, a magnet be energized, its lever 119 will be drawn down, the corresponding arm 110 will follow its pin 117 to the right on the back stroke of rod 113, the deflector of that station will be raised, and the card will be deposited in the station under the deflector. On the next stroke of rod 113 to the left, arm 110 will resume its latched position on shoulder 121. This raised position of the deflector is shown in the middle station in Fig. 3, in which it will be noticed that the brushes to the right have both contacted through their card, thereby energizing the magnet of the center station and causing the card through which contact was made, to go into the station corresponding to that magnet.

Electric system.

On the same shaft with picker drum 61 is a gear 122, geared in the ratio 4 to 1 to the smaller gear 123, so that gear 123 makes one revolution for each card fed from the stack. Secured to gear 123 is the cam 124, operating against the spring blade 125 to make and break contact 126. The drawing illustrates only part of the cam contact combination, which is the conventional cam and contact device used in tabulating and sorting machines, driven synchronously with the card movement to make the brush circuit just before a perforation reaches the brush and break the circuit just before the brush leaves the perforation in the card. This device is shown diagrammatically in Fig. 11^a, at the left.

Referring to Figs. 11 and 11^a the motor 33 is started by depressing start key 127. This closes a circuit from source 215, switch 216 having been previously closed, through the stop keys 128, through control relay R-1, motor relay R-2 and back to the other side of source. Cards now start to pass through the machine and upon actuation of the card lever 129 the card lever contacts 220 close and maintain relay R-1 energized so long as cards continue passing through the machine or until one of the stop keys 128 is depressed. The opening of contacts 220 or the depression of one of the stop keys 128 will open the circuit of relay R-1 thus cutting motor relay R-2 out of circuit and interrupting the circuit to motor 33. The contact mechanism 124 is so timed that it sends an impulse to a control circuit 221 once for every card cycle, the impulse occurring while the control zone of the card is under the brushes. As shown in the diagram there are a number of branch circuits 222 connecting to the control circuits, connection being made through individual

switches 130. Magnets 107 are disposed in the circuits 222 and from the individual magnets 107 circuits 223 are provided which go to the brush analyzing mechanism. As clearly shown in the diagram the arrangement is such that the passage of the current through the brushes and contact members is in series if multiple brushes are employed. After passing through the brush or brushes current returns to return line 224 through the return leads 225, one of which leads is provided for each brush combination. As shown in Fig. 11 a return wire 226 is provided from the return control line 224 which extends to and connects with the opposite side of the source of current. It will be understood that if at the instant a brush or a pair of serially connected brushes rests upon a blank card or upon a blank portion of the card, no contact will be established through the card with contact strips 105. Then no circuit is completed through the brush circuit, the magnet 107 will not be energized, the deflector will remain down and the card will pass on to the next station for further examination.

If, however, a single brush finds a hole, or a double brush both its holes, at the time the impulse is sent through the control circuit, then the magnet controlled by that brush will act, its deflector will be raised, and the card will go into the station under the deflector.

The stations are arranged in the order 9, 8, 7, 6, 4, 3, 2, 1, 0, and 5, so the cards will pass through all the two-brush analyzing devices before reaching the one-brush stations, otherwise some single brushes would actuate deflectors by making contact through single holes of two-hole combinations. For instance, the 5 brush would act for all cards having holes in C position thus including all 3, 8, and 9 cards. However, due to my sequence of stations, all 3, 8, and 9 cards are sorted before station 5 is reached.

Single digit operation.

Before beginning to sort a promiscuous stack of cards the operator sets the brush holders 101 on rods 100 so the brushes 104 will traverse the card column to be analyzed and sorted.

While my sorter is in operation contact is made at 126 once for every card cycle, and a contact is made at the instant the card is in proper position on the contact blocks 105 for the brushes to properly analyze the perforations in the card, as previously explained.

If a set of brushes finds its particular combination of holes its magnet is energized, its deflector raised, and the card will go into the station under that deflector. If a set of brushes finds its particular combination, it acts, otherwise it lets the card pass on to be examined again at each succeeding station.

If no combinational holes are found in the column of the control zone being analyzed, the card will pass to the final station, marked R, or reject.

5 The above description covers straight sorting, and it is evident that the cards are analyzed and sorted rapidly, without stopping the cards, and each card is deposited in its appropriate station.

10 My device may also be used for selecting only cards having only one particular hole combination in the path of the brushes, as for instance the 6 combination, in which case all brush circuit switches 130 will be opened, except the one at station 6. All 6 cards will then go to the 6 station, the others all going to the R station.

15 To sort more than one combinational set of holes in a single column, as for instance 9 and 7, all switches except 9 and 7 are opened. Then all cards with a 9 combination will go to the 9 station and all cards with a 7 combination will go to the 7 station, all other cards going to the R station.

20 25 Another valuable feature of my present invention is its ability to sort in more than one column at a time, in one run. This is possible on account of having a settable brush at each station. Suppose, for instance, the operator wants to take out all cards having a 9 combination in the first column, and all those having the 2 combination in the seventh column. At the 9 station the brushes are positioned to the first column, and at the 2 station the brush is positioned at the seventh column. All other brush circuits are opened. Then when the cards are run through, all cards with 9 in the first column will go to station 9. All cards with 2 in the seventh column, without 9 in the first column, will go to the 2 station. The cards in the 9 station will then be run through again with only the 2-brush circuit alive. In this way the cards with 9 in the first column will pass on to the 2 station without hindrance, and any of them with 2 holes in the seventh column will go to the 2 station.

Plural-digit sorting..

50 I shall now describe the design and operation of the plural-digit devices as embodied in the first two stations of my machine, the station nearest the feed mechanism being designated Z, and the next one Y.

55 The rolls, conveyor system, and magnet control of the deflector are all the same as in the single-digit device, but the analyzing features are so modified as to enable them to sort out plural-digit numbers from Peirce cards.

60 For instance, suppose it is desired to sort out all cards having the combination shown in the last four columns of the control zone of the card in Fig. 9, which portion of the control zone I have marked Y. Reference to the

code in Fig. 10 shows the number represented by the holes in section Y to be 3785.

65 After the card emerges from the micrometer openings 72, and before reaching the deflector of the Y station, it passes under a set of sixteen brushes 204 which normally contact with sixteen contact pads 205, spaced to correspond to the index positions on the card, as shown in Fig. 7. The brushes are held by non-conducting brackets 206 and the contact pads by the non-conducting bracket 70 207. Both brackets 206 and 207 extend crosswise of the machine and are rigidly fastened thereto at their ends (Fig. 4).

75 80 Each brush is wired to a tap in the plug board 208, and each pad is wired to a tap in the plug board 209, both plug boards extending from the side of the machine as indicated in Figs. 4 and 6. This arrangement allows the operator to so connect up his plug board that the circuit will be complete through the 85 brushes only when the predetermined combination of holes is under the brushes.

90 95 The wiring is arranged in the plug boards in Fig. 4 and in the diagram in Fig. 11 so the brush circuit is complete only when the combination representing 3785 is under the brushes, which combination allows current to flow from the common line 210 down through the C brush in the digits column, then through the brushes in the tens, hundreds, and thousands columns, and finally out from the pad under the A brush in the thousands column and into the return line at 211.

100 105 If a card with this combination of holes is under the brushes when contact is made at 126 the brush circuit will be complete, magnet Y-107 will be energized, deflector Y-108 will be raised, and the card will go into the Y station, where it belongs. It is evident also that if the plug board be wired 110 as shown no other combination of card perforations will allow completion of the circuit, and such cards will pass on for further examination at succeeding stations.

110 115 If it be desired to sort out a plural-digit number from some other section of the control zone, as for instance the section marked Z, then that set of brushes and contact pads through which the Z section of the card will pass, is wired at its plug boards just as described above for section Y, but for the correct combination. Fig. 7 shows the Z contact pads, and Fig. 11 shows the Z plug boards before the combination is set up on them. The Z section of the control zone in Fig. 9 represents 1260 according to the code, so if both plug boards are wired up and the sorter started, all cards reading 1260 in the Z section will go into the Z station, all cards reading 3785 in the Y section will go into the 120 Y station, and all cards showing neither of the above combinations will pass on for single-digit sorting. I have shown only two

plural-digit stations, but as many may be used as the capacity of the card permits. I also contemplate shifting the brushes for the multiple digit reading brushes in the same 5 manner as provided for the single-digit brushes. With such a construction suitable provision must be made for securing individual column and position contacts.

In accordance with the provisions of the 10 patent statutes, I have herein described the principles of operation of my invention, together with the apparatus which I now consider to represent the best embodiment thereof, but I desire to have it understood that the 15 apparatus disclosed is purely illustrative and that the invention may be carried out by other means. Also, while it is designed to use the various features and elements in the 20 combinations and relation described, some of these may be altered and others omitted and some of the features of each modification 25 may be embodied in the others without interfering with the more general results outlined, and the invention extends to such use.

25 What I claim is:—

1. In a machine of the character described, in combination with means for feeding record cards, means to segregate in one run cards having any desired combination of combinational 30 holes in a plurality of columns.

2. In a machine of the character described, in combination with means for feeding record cards, means to analyze combinational holes of said cards while the cards are in motion, 35 and means to segregate in one run cards having any desired combination of holes in a plurality of columns.

3. In a machine of the character described, in combination with means for feeding record 40 cards, means to analyze combinational holes of said cards by means of electric currents flowing through holes in the cards, and means to segregate in one run cards having any desired combination of holes in a plurality of 45 columns.

4. In a machine of the character described, in combination with means for feeding record cards, means to analyze combinational holes of said cards by passing electric currents 50 through the holes while the cards are in motion, and means to segregate on one run cards having any desired combination of holes in a plurality of columns.

5. In a machine of the character described, 55 in combination with means for feeding record cards, means to analyze combinational holes of said cards by means of electric currents flowing through holes in the cards, and magnetic means controlled by said analyzing 60 means to segregate in one run cards having any desired combination holes in a plurality of columns.

6. In a machine of the character described, 65 in combination with means for feeding record cards, means to analyze combinational holes

of said cards by means of electric currents flowing through holes in the cards, and means to segregate in one run cards having any desired combination of holes in a plurality of columns, said analyzing means comprising a 70 plurality of contact brushes.

7. In a machine of the character described, in combination with means for feeding record cards, means to analyze combinational holes of said cards by passing electric currents 75 through the holes while the cards are in motion, and magnetic means controlled by said analyzing means to segregate in one run cards having any desired combination of holes in a plurality of columns.

8. In a machine of the character described, in combination with means for feeding record cards, means to analyze combinational holes of said cards by passing electric currents through the holes while the cards are in motion, and means to segregate in one run cards having any desired combination of holes in a 85 plurality of columns, said analyzing means comprising a plurality of contact brushes.

9. In a machine of the character described, in combination with means for feeding record cards, means to analyze combinational holes of said cards by means of electric currents flowing through holes in the cards, and means to segregate in one run cards having any desired combination of holes in a plurality of 95 columns, said analyzing means comprising a plurality of contact brushes and a plurality of corresponding contact pads.

10. In a machine of the character described, in combination with means for feeding record cards, means to analyze combinational holes of said cards by passing electric currents through the hole while the cards are in motion, and means to segregate in one run 100 cards having any desired combination of holes in a plurality of columns, said analyzing means comprising a plurality of contact brushes and a plurality of corresponding contact pads.

11. In a machine of the character described, in combination with means for feeding record cards, a plurality of receiving stations, means at each station to analyze combinational holes in said cards, and means at 115 each station to segregate in one run cards having any desired combination of holes in a plurality of columns.

12. In a machine of the character described, in combination with means for feeding record cards, a plurality of receiving stations, means at each station to analyze combinational holes in said cards while the cards are in motion, and means at each station to segregate in one run cards having any desired combination of 120 holes in a plurality of columns.

13. In a machine of the character described, in combination with means for feeding record cards, a plurality of receiving stations, means at each station to analyze combinational holes 130

- in said cards by passing electric currents through the holes, and means at each station to segregate in one run cards having any desired combination of holes in a plurality of columns. 5
14. In a machine of the character described, in combination with means for feeding record cards, a plurality of receiving stations, means at each station to analyze combinational holes in said cards by passing electric currents through the holes while the cards are in motion, and means at each station to segregate in one run cards having any desired combination of holes in a plurality of columns. 10
15. In a machine of the character described, in combination with means for feeding record cards, a plurality of receiving stations, means at each station to analyze combinational holes in said cards by passing electric currents through the holes, and magnetic means at each station to segregate in one run cards having any desired combination of holes in a plurality of columns. 20
16. In a machine of the character described, in combination with means for feeding record cards, a plurality of receiving stations, means at each station to analyze combinational holes in said cards by passing electric currents through the holes while the cards are in motion, and magnetic means at each station to segregate in one run cards having any desired combination of holes in a plurality of columns. 30
17. In a machine of the character described, in combination with means for feeding record cards, a plurality of receiving stations, means at each station to analyze the combinational holes upon a portion of the control zone, and means at each station to segregate in one run cards having any desired combination of holes in a plurality of columns in said portion of the control zone. 35
18. In a machine of the character described, in combination with means for feeding record cards having a combinational hole system of index perforations arranged in a control zone, a plurality of receiving stations, means at each station to analyze the combinational holes upon a portion of the control zone by passing electric currents through said holes, and magnetic means at each station to segregate in one run cards having any desired combination of holes in a plurality of columns in said portion of the control zone. 45
19. In a machine of the character described, in combination with means for feeding record cards, a control circuit, means to analyze combinational holes in said cards by means of electric currents flowing through holes in the cards, and means to segregate in one run cards having any desired combination of holes in a plurality of columns, said analyzing means comprising a plurality of contact brushes together with means to complete said control circuit when, and only when, the desired combination of holes is under the brushes. 55
20. In a machine of the character described, in combination with means for feeding record cards, a control circuit, means to analyze combinational holes in said cards by means of electric currents flowing through holes in the cards while the cards are in motion, and means to segregate in one run cards having any desired combination of holes in a plurality of columns, said analyzing means comprising a plurality of contact brushes together with means to complete said control circuit when, and only when, the desired combination of holes is under the brushes. 70
21. In a machine of the character described, in combination with means for feeding record cards, a control circuit normally open, means to analyze combinational holes in said cards by means of electric currents flowing through holes in the cards, and magnetic means to segregate in one run cards having any desired combination of holes in a plurality of columns, said analyzing means comprising a plurality of contact brushes together with means to complete said control circuit when, and only when, the desired combination of holes is under the brushes. 80
22. In a machine of the character described, in combination with means for feeding record cards, a control circuit normally open, means to analyze combinational holes in said cards by means of electric currents flowing through holes in the cards while they are in motion, and means to segregate in one run cards having any desired combination of holes in a plurality of columns, said analyzing means comprising a plurality of contact brushes and a plurality of contact pads, together with means to complete said control circuit through said control brushes and said contact pads when, and only when, the desired combination of holes is under the brushes. 90
23. In a machine of the character described, in combination with means for feeding record cards, a control circuit normally open, a plurality of contact brushes cooperating with combinational holes upon the card to analyze the holes while the card is in motion, and means comprising a plug board permitting said contact brushes to be so wired as to complete the control circuit when, and only when, a desired combination of holes in a plurality of card columns is under the brushes. 100
24. In a machine of the character described, in combination with means for feeding record cards, a control circuit normally open, a plurality of contact brushes cooperating with combinational holes upon the card to analyze the same while the card is in motion, a plurality of corresponding contact pads, and means comprising a plug board for the brushes and a plug board for the contact 115

- 130

pads, permitting said brushes and said pads to be so wired as to complete the control circuit when, and only when, a desired combination of holes in a plurality of card columns is under the brushes.

25. In a machine of the character described, in combination with means for feeding record cards, a control circuit, a combinational hole analyzing means comprising a plurality of contact brushes in series in said control circuit, a magnet in said control circuit in series with the brushes, and a deflector operable by the magnet.

26. In a machine of the character described in combination with means for feeding record cards, a control circuit, a combinational hole analyzing device comprising a plurality of contact brushes in series in said control circuit and arranged to analyze cards while the cards are in motion, a magnet in said control circuit in series with the brushes, and a deflector operable by the magnet.

27. In a machine of the character described, in combination with means for feeding record cards, a plurality of receiving stations, combinational hole analyzing means including a control circuit at each station, a magnet in each control circuit, a deflector at each station controlled by said magnet, each of said deflectors being normally in non-deflecting position but movable to deflecting position when the magnet is energized.

28. In a machine of the character described, in combination with means for feeding record cards, a plurality of receiving stations, a control unit at each station, said control unit including a combinational hole analyzing means comprising one or more contact brushes, a magnet, a deflector, and a control circuit, said brushes and said magnet being in series in said control circuit, and said deflector being operable by said magnet.

29. In a machine of the character described, in combination with means for feeding record cards a plurality of receiving stations, a control unit at each station, said control unit including a combinational hole analyzing means comprising one or more contact brushes and arranged to analyze cards in motion, a magnet, a deflector, and a control circuit, said brushes and said magnet being in series in said control circuit, and said deflector being operable by said magnet.

30. In a machine of the character described, in combination with means for feeding record cards, a feeding device, a plurality of receiving stations, a conveyor common to all the stations, a control unit at each station; said control unit including a combinational hole analyzing means comprising one or more contact brushes, a magnet, a deflector, and a control circuit; said brushes and said magnet being in series in said control circuit, and said deflector being operable by said magnet.

31. In a machine of the character described, in combination with record cards a feeding device, a plurality of receiving stations, a conveyor common to all the stations, a control unit at each station; said control unit including a combinational hole analyzing means comprising one or more contact brushes and arranged to analyze cards in motion, a magnet, a deflector, and a control circuit; said brushes and said magnet being in series in said control circuit, and said deflector being operable by said magnet.

32. In a machine of the character described, in combination with record cards, a plurality of receiving stations, a control unit at each station; said control unit including a combinational hole analyzing means comprising one or more contact brushes, a magnet, a deflector, and a control circuit; said brushes and said magnet being in series in said control circuit, and said deflector being operable by said magnet.

33. In a machine of the character described, in combination with record cards, a plurality of receiving stations, a control unit at each station; said control unit including a combinational hole analyzing device comprising one or more contact brushes, a magnet, a deflector, and a control circuit; said brushes and said magnet being in series in said control circuit, said deflector being operable by said magnet; and means to permit said analyzing devices to analyze more than one section on the card, in one run.

34. In a machine of the character described, in combination with record cards, a plurality of receiving stations, a control unit at each station; said control unit including a combinational hole analyzing device comprising one or more contact brushes, a magnet, a deflector, and a control circuit; said brushes and said magnet being in series in said control circuit, said deflector being operable by said magnet; and settable means to render any of said control units inoperative.

35. In a machine of the character described, in combination with record cards, a plurality of receiving stations, a combinational hole analyzing device at each station, a magnet controlled by said analyzing device at each station, a deflector controlled by said magnet at each station, a push rod common to all the stations, said push rod moving all deflectors to non-deflecting position once every card cycle each of said deflectors being released to deflecting position by its corresponding magnet whenever said magnet is energized by its corresponding analyzing device.

36. In a machine of the character described, in combination with record cards, a device for feeding cards at equal intervals, a conveying means which preserves said equal intervals, a plurality of control circuits, and a plurality of combinational hole analyzing devices, said analyzing devices each comprising

- ing one or more contact brushes together with means to complete said control circuit through said contact brushes in series when, and only when, the proper combination of holes is under the brushes.
37. In a machine of the character described, in combination with record cards, a plurality of receiving stations, means at each station to analyze combinational hole cards, and means at each station to segregate cards under control of said analyzing device; some of said analyzing devices being arranged to analyze only one column on the cards, others of said analyzing devices being arranged to analyze any desired combination of holes in a plurality of columns on the cards.
38. In a machine of the character described, in combination with record cards, a plurality of receiving stations, a conveyor system common to all said stations, means at each station to analyze combinational hole cards, and means at each station to segregate cards under control of said analyzing means; some of said analyzing devices being arranged to analyze only one column on the cards, others of said analyzing devices being arranged to analyze any desired combination of holes in a plurality of columns on the cards; said conveyor system being so designed as to carry cards first through the plural column analyzing devices and then carry the remaining cards through the single column analyzing devices.
39. In a machine of the character described, in combination with record cards, a plurality of devices to analyze combinational holes of the cards, some of said devices being arranged to analyze single card columns and others of said devices being arranged to analyze a plurality of columns, in one run.
40. In a machine of the character described, in combination with record cards, a plurality of devices to analyze combinational hole cards in motion, some of said devices being arranged to analyze single card columns and others of said devices being arranged to analyze a plurality of card columns, in one run.
41. In a machine of the character described, in combination with record cards, a plurality of devices to analyze combinational hole cards by passing electric currents through the holes, some of said devices being arranged to analyze single card columns and others of said devices being arranged to analyze a plurality of card columns, in one run.
42. In a machine of the character described, in combination with record cards, a plurality of devices to analyze combinational hole cards in motion, some of said devices being arranged to analyze single card columns and others of said devices being arranged to analyze a plurality of card columns, in one run.
43. In a machine of the character described, in combination with record cards, a plurality of receiving stations, a combinational hole analyzing device at each station, each analyzing device being effective only on card index perforations corresponding to its own station, and a card deflecting device controlled by each analyzing device, some of said analyzing devices analyzing single columns and others analyzing plural columns on the cards.
44. In a machine of the character described, in combination with record cards, a plurality of receiving stations, a combinational hole analyzing device at each station to analyze cards in motion, each analyzing device being effective only on card index perforations corresponding to its own station, and a card deflecting device controlled by each analyzing device, some of said analyzing devices analyzing single columns and others analyzing plural columns on the cards.
45. In a machine of the character described, in combination with means for feeding record cards, a plurality of receiving stations, a card segregating device at each station, each segregating device responding only to hole combinations corresponding to its own station, some of said segregating devices being controlled by single-column hole combinations, and others being controlled by plural-column hole combinations.
46. In a record card controlled machine, in which means is provided for feeding record cards through the machine, and means for analyzing the said cards for combinational perforations while the latter are in motion, said analyzing device comprising brushes co-operating with the cards and forming parts of control circuits which serially connect such brushes which read multiple hole combinations.
47. In a card sorting machine, in combination with means for feeding record cards through the machine, a plurality of receiving stations, means for analyzing a plurality of separate items on said cards, each said separate item comprising combinational perforations in at least a plurality of columns, and means controlled by said analyzing means for segregating in one run cards representing each separate item into separate receiving stations.
48. In a machine of the character described, in combination with means for feeding record cards, a plurality of receiving stations, and an analyzing device at each station for analyzing a combinational hole system of index perforations, said analyzing device being arranged to analyze the cards while the cards are in motion.
49. In a machine of the character described, in combination with means for feeding cards, a plurality of receiving stations, and an analyzing device at each station for analyzing a combinational hole system of index perforations said analyzing devices being arranged to analyze the cards by causing electric currents to flow through holes in the cards while the cards are in motion.

50. In a machine of the character described, in combination with means for feeding record cards, a plurality of receiving stations, analyzing means at each station for analyzing a combinational hole system of index perforations, and a deflecting device controlled by the analyzing means at each station, said analyzing means being arranged to analyze the cards while the cards are in motion.

51. In a machine of the character described, in combination with means for feeding record cards, a plurality of receiving stations, analyzing means at each station for analyzing a combinational hole system of index perforations and a magnetically operated deflecting device at each station, each deflecting device being controlled by the analyzing means at the same station, said analyzing means being arranged to analyze cards by causing electric currents to flow through holes in the cards while the cards are in motion.

52. In a machine of the character described, in combination with means for feeding record cards, and a plurality of devices to analyze said cards for a combinational hole system of index perforations while the cards are in motion, each of said devices being settable to analyze any desired column on the card.

53. In a machine of the character described, in combination with means for feeding record cards, and a plurality of devices to analyze said cards for a combinational hole system of index perforations while the cards are in motion, said analyzing devices being settable to analyze one or more card columns in one run.

54. In a machine of the character described, in combination with means for feeding record cards, a plurality of receiving stations, a device at each station to analyze cards for a combinational hole system of index perforations by causing electric currents to flow through holes in the cards, and a deflector at each station, each of the deflectors being magnetically operable by its corresponding analyzing device.

55. In a machine of the character described, in combination, a device for feeding record cards at equal intervals, and a plurality of devices to analyze the cards for a combinational hole system of index perforations while the cards are in motion.

56. In a machine of the character described, in combination with means for feeding record cards, a device for feeding cards at equal intervals, a conveying means which preserves said equal intervals, and a plurality of devices to analyze the cards for a combinational hole system of index perforations while the cards are in motion; said conveying means comprising successive sets of upper and lower driven rolls so spaced that each set

of rolls receives the card before the preceding set has released it.

57. In a machine of the character described, in combination with means for feeding record cards, a device for feeding cards at equal intervals, a conveying means which preserves said equal intervals, and a plurality of devices to analyze the cards for a combinational hole system of index perforations while the cards are in motion; said conveying means comprising successive sets of upper and lower driven rolls, the successive sets of rolls being spaced apart a distance less than the width of a card.

58. In a machine of the character described, in combination with means for feeding record cards, a feeding device, a plurality of receiving stations, a conveyor common to all the stations, a device at each station to analyze the cards for a combinational hole system of index perforations in motion, and a card deflecting means controlled by each analyzing device.

59. In a machine of the character described, in combination with means for feeding record cards, a feeding device, a plurality of receiving stations, a conveyor common to all the stations, a device at each station to analyze cards for a combinational hole system of index perforations by passing electric currents through holes in the cards while the cards are in motion, and a card deflecting means magnetically controlled by each analyzing device.

60. In a machine of the character described, in combination with means for feeding record cards at equal intervals, a rotary feed roll conveyor system which preserves the equal distances between cards, a plurality of receiving stations, an analyzing device at each station for analyzing a combinational hole system of index perforations, each analyzing device being effective while the cards are in motion and only on card index positions corresponding to its own station.

61. In a machine of the character described, in combination with means for feeding record cards at equal intervals, a conveyor system which keeps the cards in continuous motion and preserves the equal distances between cards, a plurality of receiving stations, an analyzing device at each station for analyzing for a combinational hole system of index perforations, each analyzing device being effective while the cards are in motion and only on the combinational hole index perforations corresponding to its own station, and a card deflecting device controlled by each analyzing device.

62. In a machine of the character described, in combination with means for feeding record cards, a conveyor system which keeps the cards in continuous motion, a plu-

5 rality of receiving stations, an analyzing device at each station with provisions for analyzing combinational hole records while the cards are in motion, said analyzing device being settable to traverse any column on the card.

10 63. In a machine of the character described, in combination with means for feeding record cards, a conveyor system, a plurality of receiving stations, an analyzing device at each station with provisions for analyzing combinational hole records while the cards are in motion, and means permitting said analyzing devices to analyze more than 15 one column on the cards, in one run.

20 64. In a machine of the character described, in combination with means for feeding record cards, a rotary feed roll conveyor system, a plurality of receiving stations, an analyzing device at each station with provisions for analyzing combinational hole records while the cards are in motion, and settable means to render one or more of said analyzing devices inoperative.

25 65. In a machine of the character described, in combination with means for feeding record cards, a plurality of devices to analyze said cards for a combinational hole system of index perforations while the cards 30 are in motion, and settable means to render any of said analyzing devices inoperative.

35 66. In a machine of the character described, in combination with means for feeding record cards, an analyzing device for analyzing a combinational hole system of index perforations while the cards are in motion and a magnet controlled by said analyzing device, said magnet being ineffective except when the proper combination of index 40 perforations is in the analyzing device.

45 67. In a machine of the character described, in combination with means for feeding record cards, a system of contact brushes for analyzing a combinational hole system of index perforations while the record cards are in motion and a magnet controlled by said brushes, said magnet being ineffective except when the proper combination of index 50 perforations, in proper location, is under said brushes.

55 68. In a machine of the character described, in combination with means for feeding record cards, a sensing device for analyzing a combinational hole system of index perforations while the record cards are in motion, a magnet, and a deflector controlled by said magnet, said magnet being effective to control said deflector when a proper combination of holes is in the sensing device 60 and ineffective when an improper combination of holes is in said sensing device.

65 69. A record controlled machine including record feeding means, means to analyze combinational index points on a moving record and means including said analyzing

means for controlling machine operation in accordance with an analyzed combination of index points as compared to a predetermined combination.

70. A record controlled machine includ- 70 ing record feeding means, means to analyze combinational index points on a moving record and means including said analyzing means for controlling machine operation in accordance with analyzed combinations in a 75 plurality of record columns.

71. A record controlled machine includ- 80 ing record feeding means, means to analyze combinational index points on a moving record, electrical means for controlling ma- 85 chine operation, a control circuit therefor and circuit closing means in said circuit controlled conjointly from a plurality of index point combinations in different record columns.

85 72. A record controlled machine includ- 90 ing record feeding means, means to analyze combinational index point perforations on a moving record comprising coacting contacts on opposite sides of the record and mov- 95 able through the perforations to establish electric contact and means including said analyzing means for controlling machine operation in accordance with an analyzed combination of index points as compared to a 100 predetermined combination.

100 73. A record controlled machine including record feeding means, means to analyze combinational index point perforations on a moving record comprising coacting contacts on opposite sides of the record and movable through the perforations to establish electric contact and means including said analyzing means for controlling machine operation in accordance with conjoint analyses in a 105 plurality of record columns.

105 74. A record controlled machine including record feeding means, means for analyzing combinational index points on a moving record, said means including selecting means for predetermining combinations to be analyzed and means including said analyzing means for controlling machine operation in accordance with the presence or absence of the pre- 110 determined combinations on a controlling record.

110 75. A record controlled machine including record feeding means, means for analyzing combinational index points in each of a plurality of columns of a moving record, said 115 means including selecting means for predetermining combinations to be analyzed in the several columns and means including said analyzing means for controlling machine operation conjointly from the several columns in accordance with the presence or absence of the predetermined combinations in the several columns.

120 76. A record controlled machine including an electrically operated controlling device,

means for analyzing combinational index point perforations on a moving record comprising pairs of coacting contacts on opposite sides of the record, one contact of each pair being movable through perforations in records to engage its coacting contact and a control circuit for said controlling device including said pairs of contacts in series.

77. A record controlled machine including an electrically operated controlling device, means for analyzing combinational index point perforations in a plurality of record columns concurrently while the record is in motion, said means including pairs of coacting contacts on opposite sides of the record, one contact of each pair being movable through perforations in records to engage its coacting contact and a control circuit for said controlling device including said pairs of contacts in series whereby machine operation may be controlled conjointly from a plurality of columns on a moving record each of which columns may contain a plurality of index points.

78. A record controlled machine including record feeding means, means to analyze combinational index points on a moving record, means including said analyzing means for controlling machine operation in accordance with an analyzed combination of index points as compared to a predetermined combination

and selective means for selecting the predetermined combination.

79. A record controlled machine including record feeding means, means to analyze combinational index points in a plurality of columns of a moving record, means including said analyzing means for controlling machine operation in accordance with the conjoint analysis of the several columns as compared to a predetermined combination and selective means for selecting the predetermined combination.

80. A record controlled machine including an electrically operated controlling device, means for analyzing index point perforations on a moving record, said means including pairs of contacts on opposite sides of the record, one contact of each pair being movable through perforations in records to engage its coacting contact, a control circuit for said controlling device and selective means for connecting in series in said circuit any number of pairs of contacts associated with any desired index point analyzing position in the same or different record columns whereby machine operation may be controlled conjointly from any number of index point positions.

In testimony whereof I hereto affix my signature.

JAMES W. BRYCE.
